UNITED STATES PATENT OFFICE.

JACOB FELBEL, OF NEW YORK, N. Y., AND CARL GABRIELSON, OF GREENVILLE, NEW JERSEY; SAID GABRIELSON ASSIGNOR TO SAID FELBEL.

TYPE-WRITING MACHINE.

SPECIFICATION forming part of Letters Patent No. 699,796, dated May 13, 1902.

Application filed May 14, 1901. Serial No. 60,157. (No model.)

To all whom it may concern:

Be it known that we, JACOB FELBEL, of the borough of Manhattan, in the city, county, and State of New York, and CARL GABRIELSON, of Greenville, in the county of Hudson and State of New Jersey, citizens of the United States, have invented certain new and useful Improvements in Type-Writing Machines, of which the following is a specification.

10 This invention relates more particularly to front-strike writing-machines of the type illustrated in the patent granted to Jacob Felbel, No. 657,927, dated September 18, 1900.

The objects of the invention are to provide 15 an improved controller for the antifriction-balls upon which the paper-carriage runs; to improve the mounting of the releasable paper-carriage spacing-rack; to enable the margin-gage bar arranged in rear of the platen 20 to be rocked by a key at the keyboard, so as to unlock the type-operating keys and also to permit additional movement of the paper-carriage; to improve the feed of the paper around the platen; to improve the mounting 25 of the adjustable front paper-guides; to provide improved gages for the side edges of the paper, whereby the latter is guided into the machine; to provide a conveniently attached and detached envelop or card-guide; to im-

30 prove the mounting of the paper-shelf so that it may be swung forwardly for affording access to the margin-gage bar and return automatically to its normal position, and also so that it may be readily detached from the carriage when desired, and to provide an improved support for the platen-scale.

To these ends the invention consists in combinations of devices, features of construction, and arrangements of parts, all as will be fully 35 hereinafter set forth, and particularly pointed out in the concluding claims.

In the accompanying drawings, Figure 1 is a sectional side elevation of a machine of the type illustrated in said patent and showing 40 the present improvements applied thereto. Fig. 2 is a sectional view illustrating certain improvements in the mounting of the paper-feeding pressure-rollers. Fig. 3 shows a cross-section of a rear longitudinal bar forming 45 part of the carriage-frame and of a ball-controller associated therewith. Figs. 4 and 5

are front views of the main carriage-bar, fixed carriage-rails, and key-locking and margin-gage devices, the former figure showing the key-locking position of the parts and the latter showing the margin-gage bar rocked by a key at the keyboard, so as to release the type-operating keys and enable additional movements of the paper-carriage. Fig. 6 is an end view illustrating the releasing movement of 60 the margin-gage bar. Fig. 7 is a perspective view of the ball-controller employed in connection with the carriage and showing its relation to the carriage and carriage-rails. Fig. 8 is a perspective view of a novel form of paper-gage. Fig. 9 is a rear elevation of the paper-shelf detached from the carriage. Fig. 10 is a front view of the carriage. Fig. 11 is a plan of the rear part of the paper-carriage, illustrating the manner of mounting a releasable letter-spacing rack thereon. Fig. 12 is a cross-section showing a detail of the carriage-rack release. Fig. 13 is a plan of an adjustable front paper-guide and its connected paper-gage both mounted upon a bar extending longitudinally over the platen. Fig. 14 is a plan taken at the right-hand side of the machine and illustrating the connections 75 extending from the rocking margin-gage bar to the keyboard.

In the several views similar parts are designated by similar numerals of reference and certain portions are omitted or broken away for the sake of disclosing the invention more clearly.

The framework of the machine comprises a base 1, corner-posts 2, and a top plate 3. Rearwardly-striking type-bars 4, resting at their forward ends upon a curved pad 5 and pivoted at their rear ends upon a curved wire 6, mounted in a segment 7, are swung upwardly and rearwardly upon said wire by means of links 8, connected to the upper ends of levers 9, the latter being pivoted near their lower ends at 10 upon key-levers 11 of the 90 second order, said key-levers being fulcrumed upon a transverse rod 12 and the levers 9 having portions which extend below the key-levers and are provided with open horizontal slots 13 for engaging a transverse fulcrum- 95 rod 14, so that when the key-levers 11 are depressed the upright levers 9 are caused to 100

swing rearwardly and pull the type-bars up to print, the latter being provided with returning-springs 15. The types strike upon the front side of a cylindrical platen 16, which 5 is mounted upon a shaft 17, journaled in the forward ends of side arms 18, whose rear ends are secured at 19 to a slide 20, extending longitudinally of the platen, said arms 18 and slide 20 together constituting a bail-like carriage-frame. The slide is provided along its upper and lower edges with ball-bearing grooves 21, which match grooves 22, formed, respectively, in the upper side of an underlying rail 23 and in the under side of a rail 15 24, overhanging said slide, antifriction-balls 25 being placed in the grooves and said rails 23 and 24 being clamped by screws 26 to bosses 27, formed upon the front side of brackets 28, erected upon the top plate 3, so that 20 the carriage as a whole is suspended by the rails 23 and 24, from which it extends forwardly. The carriage is propelled, as usual, by a spring (not shown) and carries a longitudinal letter-spacing rack 29, adapted to engage a pinion (not shown) usually connected to an escapement-wheel 30, whose movements are controlled by escapement-dogs 31 and 32, carried upon the upper end of a rocker 33, mounted in a depending bracket 34 and connected by arms 35 and hooks 36 to a universal bar 37, extending transversely beneath the type-operating key-levers 11, whereby at the 25 operation of any of the latter the carriage is permitted to advance a letter-space.

35 Preferably a set of two balls 25 is placed in each of the upper and lower raceways. The balls in the lower set are confined in perforations 38, formed at the ends of a lower spacer 39, lying flatwise between the carriage-bar 20 40 and the lower rail 23, while the balls in the upper set are confined in similar perforations formed in the end portions 40 of an upper spacer, the latter being connected to the lower spacer by a pair of arms 41, which are bent to follow the contour of the carriage-bar 20. The main portion 42 of the upper spacer is offset from the end portion 40 by means of short upwardly-bent arms 43 and lies on edge just forwardly of the upper rail 24. The 45 parts numbered from 39 to 43, inclusive, are formed integrally from thin sheet metal and constitute a light traveling frame, whereby all of the balls in the upper and lower sets are connected, so that their relative arrangement is constantly preserved. In order to prevent the balls from creeping or working out of their proper positions longitudinally of the paper-carriage, the spacer 42 is provided upon its under edge with rack-teeth 55 60 44, which mesh with a pinion 45, pivotally mounted upon a shoulder-screw 46, tapped into the carriage-slide 20, about midway of the length of the latter, said pinion being fixed to a pinion 47 of twice its own diameter, and the latter being in mesh with a horizontal rack 48, arranged longitudinally in front of the upper rail 24 and fixed thereon

by screws 49, collars 50 being placed upon the latter between the rack and the rail, so as to slightly separate them, and thus afford a clearance for the spacer-rack 42. Since the common axis 46 of the pinions travels together with the carriage-slide 20 and since the pinion 47 meshes with the fixed rack 48 and is of double the diameter of the pinion 45, it 75 follows that the spacer-rack 42, meshing with the latter and arranged upon the same side of the axis 46 as the rack 48, must travel at half the speed of the carriage-slide 20, or, in other words, the gears taken together operate as a lever of the second order, the power being applied by the carriage-slide at 46, the fulcrum consisting of the fixed rack 48, and the work being performed upon the movable spacer-rack 42 at a point half-way between 80 the power 46 and the fulcrum 48, so that the movement of the spacer-rack 42 is half that of the carriage-slide 20, and hence equal to the natural traveling speed of the balls 25, so that there is no liability of binding, while 90 at the same time the balls are under positive control at all times, and hence cannot creep out of their proper position relatively one to another or to the paper-carriage. It will be seen that both the controller-racks, as well 95 as the pinions, may be inexpensively formed from sheet metal and that the contrivance as a whole is simple in construction and operation, as well as very compact, the latter feature being of importance in the carriage mechanism of type-writing machines.

The letter-spacing rack 29, which occupies a position above its pinion and in rear of the carriage-slide 20, is fastened at its ends by screws 51 to flanges 52, formed upon the 105 rear ends of a pair of horizontal rocker-arms 53, thus forming a bail which is hinged to bosses 54, formed in line upon the inner-sides of the carriage-arms 18, the forward ends of said rocker-arms 53 being pinned at 55 110 upon the inwardly-projecting ends of short rock-shafts 56, journaled in said bosses 54 and having reduced portions 57 for clearance. Upon the outer ends of the rock-shafts are rigidly secured by screws 58 forwardly-extending levers 59, provided with finger-pieces 60. Depression of either lever 59 causes its shaft 57 to rock, whereby the arms 53 and rack 29 are elevated, thus freeing the carriage from the control of the escapement-wheel 30, so that it may be run rapidly in either direction. Upon release of the key 60 the rack drops into mesh with its pinion, assisted by helical springs 61, compressed between the top faces of the rocker-arms 53 and the overlying portions of the carriage-slide 120 and retained by studs 62. It will be seen at Fig. 12 that the rack 29 is rabbeted to the flanges 52, so that the bail is of solid construction, as well as firmly supported, thus 125 contributing to the accuracy of the letter-feeding action of the carriage.

Directly overlying the upper carriage-rail 24 and journaled by pintles 63 between op-

posite ears 64, rising from said rail, is a longitudinally-arranged rocker-bar 65, bearing adjustable margin-gages 66. Pivoted at 67 upon the front side of the carriage-slide 20 is 5 an elbow-lever, whose upwardly-extending arm 68 is adapted to be engaged by projections carried by said gages and whose downwardly-extending bent arm 69 is adapted to bear down a bail 70, which clasps the lower 10 carriage-rail 23 and is pivoted upon the ends of the latter by screws 71. Said bail has a slot 72, which is engaged by a pin 73, projecting from a horizontal arm 74 of an elbow-shaped locking-lever, the latter being pivot- 15 ed at 75 upon the framework and having an extending arm 76, which is hooked at 77, so as to catch beneath a forwardly-extending arm 78 of the dog-rocker 33, thereby preventing operation of the latter, and hence of the 20 type-operating keys, all as fully set forth in a patent granted to said Jacob Felbel, No. 657,928, dated September 18, 1900. Said margin-gage bar may be rocked or tilted by means of knobs 79, arranged at each end, asset forth 25 in the patent just mentioned, for the purpose of releasing the lever 68, bar 70, and hook 76, so that they may assume the Fig. 5 position, thereby unlocking dog-rocker arm 78 and the type-keys and also enabling the carriage to 30 proceed; but in order to enable said margin-gage bar to be rocked more conveniently an arm 80 is projected rearwardly therefrom, and by means of a pin 81 upon its rear end engages a vertical link 82, the lower end where- 35 of is attached to a rearwardly-extending lever 83 of the third order. Said link engages the pin 81 by means of a slot 84, so as to permit the margin-gage bar to be rocked at times without operating said link. The lever 83 is 40 suitably fulcrumed at 85 upon the right-hand inner side of the base. A lever 86, pivoted at its rear end upon a depending ear 87 and carrying at its forward or keyboard end a margin-release key 88, is ranged alongside 45 of the lever 86 and loosely connected thereto by a pin 89. The levers and the link are supported in normal position by a spring 90, compressed between a rearward extension 91 upon lever 86 and the under side of the usual 50 overhanging rear portion of the base. Upon depressing the margin-release key 88 the lever 86 is forced down and by means of the pin 89 carries down the lever 83, which, through the link 82 and arm 80, rocks the margin-gage bar, as illustrated at Fig. 6, thereby 55 releasing the carriage-lever 68 from the projection or projections 92, carried upon the adjustable devices 66. The margin-gage bar is provided with a returning spring or springs 93. Thus it will be seen that the releasing movement of the margin-gage bar may be effected without removing either hand from the keyboard, thus saving time and labor.

Paper introduced behind the platen 60 passes down between the same and a deflector 94, which extends practically the entire length of the platen and at its ends is mount-

ed by ears 95 upon a rock-shaft 96, journaled in the side arms 18 of the paper-carriage. Said deflector curves downwardly, forwardly, 70 and upwardly around the platen, terminating a little below the printing-point, and is spring-pressed against the platen in the usual manner. In the rear portion of the deflector is formed an opening 97 for a pressure-roller 98, 75 the latter extending longitudinally of the platen and journaled by a shaft 99 in the lower ends of arms 100, hanging from a shaft 101, mounted upon the upper forward side of the carriage-slide 20. Leaf-springs 102 are 80 secured at their lower ends by screws 103 upon the rear edges of the arms 100 and terminate at their upper ends just beneath the shaft 101, where they bear rearwardly against the ends of adjustable abutment-screws 104, threaded 85 forwardly through the slide 20 and adapted to be adjusted so as to increase or decrease the pressure of the springs, and hence vary the pressure of the opposite ends of the roller 98 against the platen, said screws 104 being 90 nicked at their rear ends for convenient adjustment. The deflector 94 is also provided near its forward edge with an opening or openings 105 for a pressure roller or rollers 106, extending parallel with the platen and 95 mounted at 107 upon the forward end of curved arms 108, which are pivoted upon a shaft 109 and sustained by springs 110, the latter being secured at their upper ends by screws 111 and curving downwardly and forwardly and bearing up against the arms 108. 100

The front paper-guides are mounted upon a rod 112, arranged longitudinally over the platen and fixed at its ends in the side bars 18 of the carriage-frame and consist, essentially, of forwardly and downwardly curving arms 113, carrying at their forward ends pivotal mounted paper-fingers 114 and engaging said rod by perforated yokes 115, formed by bending the metal of the arms. The paper-fingers 114 are pressed against the platen by means of springs 116, which are coiled about the rod 112 and confined by the yokes 115, one end of each spring being adapted to bear upon the arm 113 and the other end thereof 115 bearing against a feather 117, formed integrally upon the rod 112. The guides may be adjusted along the rod 112 to accommodate paper of various widths. It will be seen that the feather 117 not only stiffens the rod, but 120 also gives the end of each spring a bearing comparatively remote from the axis of the rod, thereby minimizing friction between the spring and the rod when the paper-guide is moved therewith, so that said guide may 125 be readily adjusted, while the finger 114 is pressed against the platen with the necessary force.

Rearwardly-projecting gages 118 are hung upon the rod 112 by means of bent arms 119 130 and ears 120, the latter clasping the yokes 115 of the front paper-guides, so that when the latter are adjusted along the rod 112 the gages 118 are moved therewith. The ears 120

are keyed upon the said rod, as illustrated at Fig. 1, so that they cannot swing, and the gages incline or slope inwardly from top to bottom, Fig. 13, forming a sort of hopper, and hence facilitating the introduction of the paper into the machine. The gages are also disposed inwardly of the arms 113, so as to prevent the possibility of a sheet being so misplaced that it would when fed forwardly around the platen pass up beneath either of said arms 113. As will be seen at Fig. 1, the gages project rearwardly from the platen and beyond the plane of the paper-shelf, thus making it impracticable to introduce the paper in the wrong place. The arms 119 are curved substantially to match the curvature of the platen and terminate on the rear side of the latter, where they support the paper-gages 118. It will be observed by an inspection of Fig. 1 that the paper-gage is situated in rear of the platen and in the space, pocket, or angle formed by the upper rear quadrant of the platen and the lower end of the paper-table. It will also be seen that the paper-gage is of such shape that a portion of it extends down between the rear side of the platen and the upper portion of the deflector 94, which latter serves as an extension of the paper-table. By arranging the paper-gage in the space shown—that is, with its gaging-face in line with the opening or space between the platen and the deflector—the gage is out of the way and practically out of sight, and the paper may be most conveniently positioned and then fed forward without liability of change of position or adjustment, while at the same time, owing to the inset of the gage 118 with reference to the arm 113, it is impossible to put the paper in wrong and so that its leading edge will feed up under the arm 113. The paper will invariably feed inside said arm and pass up only under the paper-finger 114 and then over the rod 120 and toward the upper end of the paper-table. The arms 119 lie close to the platen, so that there is no liability of the edges of the paper catching between said arms and the platen. Referring now to Figs. 1 and 10, a small roller 121 is arranged midway of the platen and bears upon the upper front side thereof, being carried upon the end of a projecting rod 122, which is detachably secured at one end by a thumb-screw 123 in a socket 124, formed on the right-hand side arm 18 of the carriage, said rod having sufficient spring to enable the pressure-roller 121 to yield when necessary. This roller is intended for holding against the platen the middle portion of a stiff card or envelop or of a pack of sheets, so as to afford a smooth surface for the type impressions and prevent underscoring, &c. The rod 122 may be released by a turn of the screw 123 and withdrawn when not in use and conveniently replaced when desired. A paper-shelf 125, Figs. 1 and 9, is pivotally mounted by opposite screws 126 upon side arms 127 of a bail, said arms being slot-

ted at their lower ends for engaging opposite studs 128, projecting inwardly from the side arms 18 of the paper-carriage. Said shelf 125 is arranged forwardly of the detachable supporting-bail and is pivoted upon the screws 126 by means of bent ears 129, formed on the ends of a strip 130, riveted to the rear face of the paper-shelf and extending along the lower edge thereof. By means of the slotted arms 127 the paper-shelf and bail may together be detached from the machine and conveniently replaced thereon, and when in use the paper-shelf may be swung forwardly upon the pivots 126, so as to expose the margin-gage bar, over which, it will be observed, the upper portion of said shelf curves, thus making it convenient to adjust the margin-gages upon said bar. The paper-shelf is returned to normal position by springs 131, coiled around the screws 126.

A platen-scale 132, Figs. 1 and 10, is pivoted at each end by means of short rearwardly-projecting arms 133 upon the forward ends of arms 134, which are rigidly secured by screws 135 to lugs formed upon the carriage-slide and extend forwardly below the platen. By means of the hinge-arms 133 the scale is enabled to yield forwardly and downwardly to accommodate different thicknesses of paper passing around the platen. The scale is yieldingly pressed against the platen by means of springs 136, fastened upon the under sides of the arms 134 and bearing down upon rearwardly-projecting fingers 137, formed upon the scale-arms 133.

What we claim as new, and desire to secure by Letters Patent, is—

1. In a type-writing machine, the combination of a carriage-slide having grooves in its upper and lower edges, a grooved rail beneath said slide, a grooved rail above said slide, balls placed in the upper and lower grooves, a spacer 39 perforated to receive the balls in the lower grooves, arms 41 connected to said spacer, a spacer connected to the upper ends of the arms 41 and perforated to receive the balls in the upper grooves, said arms and said spacers being integral and the arms 41 extending up in rear of said carriage-slide, and the upper spacer including a forwardly-offset and upturned rack 42 occupying a position in front of the upper rail, a pinion 45 mounted upon the carriage-slide below said rack and meshing therewith, a pinion 47 having twice the diameter of pinion 45 and rigidly secured thereto, and a rack 48 mounted upon the upper rail above said pinion 47 and meshing with pinion 47.

2. In a type-writing machine, the combination of a carriage-slide, a letter-spacing rack mounted upon forwardly-extending arms so as to form a bail, rock-shafts 56 carried at opposite ends of the slide and fixed at their inner ends to the forward ends of said arms, and forwardly-extending finger-levers fixed to the outer ends of said rock-shafts.

3. In a type-writing machine, the combina-

- tion of a carriage-slide, rack 29 arranged in rear thereof, forwardly-extending arms 53 fixed upon said rack, rock-shafts 56 journaled in opposite bosses 54 and at their inner ends 5 secured to the forward ends of said arms 53, forwardly-extending levers 59 fixed to the outer ends of said rock-shafts and provided with finger-pieces 60; and a spring 61 compressed between an arm 53 and a portion of 10 said slide.
4. In a type-writing machine, the combination of a carriage-slide, a letter-spacing rack arranged in rear thereof, forwardly-extending arms having flanged ends to which said 15 rack is rabbeted and secured by screws, means for hinging the forward ends of said arms upon said slide, and a forwardly-extending finger-lever for swinging said rack.
5. In a type-writing machine, the combination 20 of a carriage-slide, a letter-spacing rack arranged in rear thereof, arms 53 having flanged rear ends 52 to which said rack is rabbeted and secured by screws 51, rock-shafts 56 mounted in opposite bosses 54 carried upon 25 the forward side of said slide and at their inner ends pinned to the forward ends of said arms 53, and forwardly-extending finger-levers 59 secured by screws 58 upon the outer ends of said rock-shafts.
- 30 6. In a type-writing machine, the combination with a carriage and suitable letter-spacing devices therefor, of a margin-gage bar extending longitudinally of the carriage and pivotally supported upon the framework, key-locking devices, including a part mounted upon said carriage and coöperating with a projection carried upon said pivoted bar, arm 80 projecting from said bar, link 82 extending upwardly from a lever 83, to said arm 80, 35 and a key-lever 86 extending to the keyboard and having means for operating said lever 83.
7. In a type-writing machine, the combination 40 with a carriage and suitable letter-spacing devices therefor, of a bar extending longitudinally of the carriage and pivotally supported upon the framework, key-locking devices including a part mounted upon said carriage and coöperating with a projection carried upon the said pivoted bar, arm 80 projecting from said bar, link 82 loosely connecting 45 lever 83 to said arm 80, key-lever 86 extending to the keyboard and having means for operating said lever 83, a spring for said pivoted bar, and a spring for said key-lever 86.
- 50 8. In a type-writing machine, the combination 55 with a carriage and suitable letter-spacing devices therefor, of a bar extending longitudinally of the carriage and pivotally supported upon the framework, key-locking devices, including a part mounted upon said carriage and coöperating with a projection carried upon said pivoted bar, arm 80 projecting from said bar, link 82 having slot 84 for engaging a pin projecting from said arm 80, lever 83 fulcrumed at one end and attached at the other end to the lower end of said link, key-lever 86 fulcrumed at its rear end and
- having a key 88 at the keyboard and having means between its ends for operating said lever 83, spring 90 for said key-lever 86, and 70 spring 93 for said pivoted bar.
9. In a type-writing machine, the combination of a carriage, lever 68 thereon, bar 70 mounted upon the framework of the machine and operable by said lever, locking-lever 76 75 connected to said bar 70, dog-rocker 33 having arm 78 adapted to be engaged by the lever 76, type-operating keys operatively connected to said dog-rocker, bar 65 extending longitudinally of the carriage and pivotally supported upon the framework, projection 92 adjustable along said bar 65 and engaged by said lever 68, arm 80 fixed upon said bar 65, link 82 having pin-and-slot connection with said arm 80, lever 83 attached at its rear end to said link and fulcrumed at its forward end, bearing-pin 89, lever 86 pivoted at its rear end and having at its forward end a key, spring 90 for said lever 86, and spring 93 for said bar 65.
10. In a front-strike writing-machine, the combination of a carriage, a platen, the detachable rod 122 supported at its outer end by the carriage and provided at its inner free end with a pressure device.
11. In a front-strike writing-machine, the combination of a carriage, a platen, the detachable spring-arm 122 attached at its outer end to the carriage and provided at its inner free end about midway of the platen with a 95 pressure-roller 121.
12. In a type-writing machine, the combination of a platen, a deflector 94 having perforations 97 and 105 and extending down the rear side of the platen and forwardly and upwardly around the same and terminating below the printing-point, pressure-roller 98 projecting through the perforation 97 in said deflector carried by pendent arms 100 having springs 102 bearing against adjustable 100 abutments 104, pressure-roller 106 passing through the perforation 105 in said deflector and carried upon the forward ends of arms 108, mounted independently of the arms 100, and provided with springs 110 fixed upon the 105 carriage and bearing against said arms 108 between the ends of the latter.
13. In a type-writing machine, the combination with a platen, of a rod 112 arranged longitudinally thereover and provided with 110 an integral feather 117, forwardly and downwardly curving arms 113 pivotally engaging said rod by means of perforated yoke 115, a spring surrounding said rod and confined in said yoke and bearing at one end upon said feather, and a pivotally-mounted paper-finger carried by the lower end of said arm and held against the platen by means of said spring.
14. In a type-writing machine, the combination with a platen, of a gage for the side 125 edge of the paper having a downwardly and inwardly sloping face.
15. In a type-writing machine, the combination with a platen, of a gage for the side

edge of the paper arranged in rear of the platen and having a downwardly and inwardly inclined face.

16. In a type-writing machine, the combination with a platen, of a rod arranged thereover, a paper-gage adjustable on said rod and comprising a rearwardly-curved arm 119 and an inclined gage 118.

17. In a type-writing machine, the combination with a platen and a paper-table arranged in rear thereof and at an angle thereto, of an adjustable paper-gage arranged in proximity to the lower end of the paper-table and in the angle between it and the rear side of 15 the platen.

18. In a type-writing machine, the combination with a platen and a paper-table arranged in rear thereof and at an angle thereto, of a paper-gage arranged in proximity to the 20 lower end of the paper-table and in the angle between it and the rear side of the platen, a curved arm carrying said paper-gage, and a rod arranged over the platen for supporting said arm.

25. 19. In a type-writing machine, the combination with a platen and a deflector, of an adjustable paper-gage arranged on the rear side of the platen and between it and the deflector.

20. In a type-writing machine, the combination with a platen and a deflector, of a rod arranged over the platen, an arm adjustable on said rod and curving rearwardly and downwardly behind the platen, and a paper-gage carried by said arm and arranged between 30 the platen and the deflector.

21. In a type-writing machine, the combination with a platen, a paper-table and a deflector, of a paper-gage arranged in the pocket or angle formed by the paper-table and deflector and the rear side of the platen.

22. In a type-writing machine, the combination with a platen, a paper-table and a deflector, of a rod arranged over the platen, a curved arm extending down in rear of the 45 platen, and a paper-gage carried by said arm and arranged in the angle or pocket formed by the rear side of the platen and the lower end of the paper-table and the upper end of the deflector.

50. 23. In a type-writing machine, the combination with the platen, the paper-table and the deflector, of a rod arranged over the platen, the arm 113 adjustable on said rod and carrying a paper-guiding device, the curved arm 55 119 also supported on said rod and adjustable with the arm 113, and a paper-gage 118 supported by the arm 119 below the top of the platen and in rear thereof and inset from the arm 113.

60. 24. In a type-writing machine, the combination of a platen, a rod mounted over the platen, a paper-guide having a part pivotally engaging said rod and extending forwardly and downwardly around the platen, and a 65 paper-gage arranged in rear of the platen and carried by an arm connected to said paper-

guide but directly engaging said rod independently of the paper-guide, the guide and the gage being adjustable together along said rod.

75. 25. In a type-writing machine, the combination with a platen, of a rod mounted thereover, a paper-guide having a supporting portion pivotally engaging said rod and extending forwardly and downwardly around the platen, and a paper-gage arranged in rear of the platen and mounted upon a depending arm which directly engages said rod by means of ears which clasp the supporting portion of said paper-guide, the latter and the gage being adjustable together along said rod.

80. 26. In a type-writing machine, the combination with a platen, of a rod arranged thereover and having an integral feather, a paper-guide having a perforated yoke portion pivotally engaging said rod and extending forwardly and downwardly around the platen and carrying at its lower end a pivotally-mounted paper-finger, a spring surrounding said rod and confined in said yoke and bearing at one end upon the latter and at the other end upon said feather, and a sloping paper-gage 118 arranged in rear of said platen and carried upon the lower end of a depending arm 119 which lies close to the platen and is 85 keyed upon said rod by means of ears 120 which clasp said yoke.

90. 27. In a type-writing machine, the combination with a carriage and a platen, of a paper-shelf having ears 129 pivotally mounted upon arms 127 which are detachably secured upon the carriage.

95. 28. In a type-writing machine, the combination with a carriage and a platen, of a paper-shelf 125, strip 130 secured thereto and having ears 129, a bail comprising arms 127 which are mounted upon the carriage, screws 126 for pivoting said ears upon said arms, and spring 131.

100. 29. In a type-writing machine, the combination with a carriage and a platen, of a spring-controlled paper-shelf pivotally mounted upon a device which is detachably mounted upon the carriage.

105. 30. In a type-writing machine, the combination with a platen and a carriage, of margin-controlling devices including a bar arranged in rear of the platen, a paper-shelf overhanging said bar and pivotally mounted upon a device which is detachably mounted 110 upon the carriage, so that said paper-shelf may be swung forwardly to expose said margin-gage bar, and a spring for returning the paper-shelf to normal position.

115. 31. In a type-writing machine, the combination with a platen and a carriage, of a support detachably mounted upon the carriage in rear of the platen, and a spring-pressed paper-shelf arranged forwardly of said support and pivotally mounted thereon.

120. 32. In a type-writing machine, the combination of a carriage having studs, a support 125

130

having forked arms which detachably engage said studs, and a spring-pressed paper-table pivotally connected to said support.

33. In a front-strike writing-machine, the combination of a carriage-slide, a platen mounted upon arms extending forwardly from said slide, a platen-scale having arms 133 upon the forward ends of arms 134 secured upon said slide, and a spring for holding said scale against the platen.

34. In a front-strike writing-machine, the combination of a carriage-slide, a platen mounted in arms extending forwardly therefrom, a platen-scale hinged by arms 133 upon

arms 134 projecting forwardly from said carriage-slide beneath the platen, and spring 136 mounted upon said arms 134 and bearing upon fingers 137 formed upon said arms 133.

Signed at the borough of Manhattan, in the city of New York, in the county of New York and State of New York, this 9th day of May, A. D. 1901.

JACOB FELBEL.
CARL GABRIELSON.
